ABSTRACT OF THE DISCLOSURE

This invention provides improved antenna arrays having characteristics that are matched with the geometric configuration of the electromagnetic waves that are to be radiated (i.e. transmitted from or received) by the array, for optimal performance. Such arrays have a greatly increased angular range of directivity. According to the invention, the spacing of the individual radiators of the array, the field-strength-distribution pattern of the energy fed to or from the individual radiators, and the phase-distribution pattern of said feed energy across the array are so predetermined and correlated that the behavior of the array as a whole is made to be substantially identical with that of an imaginary, coherently radiating aperture having the same overall configuration as the array, in respect to waves of the prescribed geometric configuration.

BACKGROUND

In the art of antenna construction, it is known to provide antenna arrays consisting of a plurality of individual, elementary antennas or radiators spaced along a predetermined direction to provide a linear array, or along each of two coordinate directions to provide a two-dimensional or surface array. Such arrays have made it possible to achieve desired directional diagrams and radiate waves having prescribed geometric configurations, for example, plane waves propagating in a prescribed direction, or spherical waves centered at a prescribed focus or source point.

In arrays of this type, it is known to feed energy to and from the individual radiators by way of phase shifters, and so to adjust the phase shifters that the phase distribution of the electromagnetic energy across the array is made to be approximately the same as that of a coherent wave having a prescribed configuration. Thus, it is obvious for example that if all the phase shifters are adjusted in like manner, then the array will radiate a plane wave propagating in a direction normal to the array. Suitable differential adjustment of the phase shifts makes it possible to simulate in an approximate manner coherent waves having any of various prescribed geometric characteristics.

For example, my co-pending application Ser. No. 583,552 of even date discloses antenna arrays of the type just indicated, which constitute secondary focusing lens assemblies and are associated with several primary antenna sources, so as to convert spherical waves radiated by a selected primary source into plane waves propagating in a controllable direction of space, and vice versa. The said copending application also disclosed digital electronic means for sequentially controlling the adjustment of the phase shifters of the array so as to accomplish what may be termed electronic scanning operation for radar and related applications.

Radiator arrays of the general class described above

2

have many important advantages including flexibility and simplicity, and are currently gaining wide acceptance in advanced radar and communication systems. However, theoretical and practical experience has revealed that such arrays as heretofore constructed suffer from certain serious defects. Thus, in the important cases where the arrays have been used for electronically controlled scanning, it has not been possible to achieve simultaneously large scanning angles and elimination of high-amplitude sidelobes while maintaining a sufficiently great spacing between the radiators of the array to avoid spurious coupling between them. To prevent the formation of such sidelobes, it was necessary instead to bring the radiators nearer to each other and thus tolerate a relatively high intercoupling or to limit the angular scanning range, or else to be content with a rather unsatisfactory compromise between the three factors: sidelobes, angular scanning, coupling. Also, spurious coupling between adjacent radiators of the array has introduced uncontrollable variations in the gain and the radiation pattern of the antenna system during scanning operations. The presence of the sidelobes, which limit the scanning angles, is due to the essentially discontinuous character of the array which permits the control of the phase of the radiated wave but at regularly equispaced points. These defects have seriously limited the usefulness of the radiator arrays of the kind to which the invention relates.

DESCRIPTION OF THE INVENTION

It is the general object of this invention to eliminate the above-noted and similar deficiencies of conventional radiator arrays in an almost complete way, and thereby greatly to improve the operating characteristics and extend the usefulness of such arrays.

According to the invention, it has been found that despite the essentially discontinuous character of the array, a consequence of the finite number of individual radiators of which it is composed, the behavior of the array in respect to waves of a prescribed geometric configuration can be made to simulate remarkably closely the theoretical behavior with reference to such waves of a fictive continuous radiant source or aperture having the same overall shape as the array. This result is reached by applying certain definite teachings, to be presently set forth, to the structural and operating parameters of the radiators of the array, so as to correlate those parameters with the specific geometric configuration of the waves to be radiated by the array. When such correlation has been achieved and the theoretical characteristics of a continuous radiant source have thereby been simulated, it is found that the operation of the array has been optimized in respect to the prescribed wave configuration. The previously observed deficiencies are virtually completely eliminated. Inter-radiator coupling is reduced practically to zero. Both the directional characteristic and the scanning range to the array can be simultaneously maximized, so long as the particular wave geometry for which the array was constructed is maintained.

Specific embodiments of the invention will now be described, for illustrative purposes and without limitative intent, with reference to the accompanying drawing, wherein:

FIG. 1 schematically illustrates a simple linear array as used in a system according to the invention for radiating plane waves of prescribed direction over a wide scanning range;

FIG. 2 illustrates part of the improved array in somewhat greater detail, together with the associated field-strength-distribution pattern used according to the invention;

FIG. 3 shows a preferred construction of an array according to the invention, using paired multimode radiators;

FIG. 4 is a curve illustrating a typical array factor; and FIG. 5 schematically illustrates the geometry of an array according to the invention when used in association with a primary source radiating spherical waves.

In the present specification and claims, the word "radiate" and its derivatives are to be construed with their broad meaning usual in antenna engineering, as applying to both the transmission and the reception of electromagnetic wave energy. Thus, an elementary antenna or radiator is said to be "radiating" energy not only when it is operating to emit as waves propagating in space electromagnetic energy fed to it, but likewise when it is picking up or absorbing space waves and transferring the energy picked up therefrom to a receiver connected by a feeder junction to said radiator. In a corresponding manner, the word "feed" and its derivatives serve to describe the transfer of electromagnetic energy by way of a conductor or waveguide both to and from a radiator.

Shown in FIG. 1 is a linear array comprising a series of radiator elements aligned on an axis O-X and numbered 1, 2, . . . n. The elements are shown at a uniform spacing designated "a." The total width of the array is $d=na$. The midpoint of the array is I and the normal to O-X at I is I-Z. An array of the kind shown may be used to radiate waves of various geometric configurations. For example, it may be desired to cause the array to radiate plane parallel waves in a prescribed direction of space defined by a specified angle α with respect to the normal I-Z, all the plane waves being normal to such prescribed direction. This requirement arises, in particular, when the array is to be used as a directional transmitting and/or receiving antenna system for transmitting radio energy e.g. in the form of radar pulses towards a target, and for receiving echo pulses from the target.

The normal way of controlling the space configuration of the waves radiated by an array is to control the phase distribution of the wave energy fed to (or from) the individual radiators of the array. If all the radiators are fed in parallel from a common signal source without any mutual phase displacement between the signals applied to the respective radiators, it is evident that the radiator array will radiate a planar wave propagating in the normal direction I-Z. If equal phase shifts are introduced between the signals applied to adjacent radiators of the array, the wave radiated from the array will still be planar, but will propagate in a direction inclined to the normal in one or the other sense, depending on the sign of the phase shift, by an angle α corresponding to the phase shift angle. Similarly, the distribution pattern of phase-shifts between the signals fed to (or from) the respective radiators of an array can be modified so as to cause the array to radiate spherical waves focused on a prescribed focal point or center, as disclosed in my co-pending application identified above and as later described. Other geometric configurations of radiated waves can similarly be obtained by controlling the phase-distribution patterns of energy fed to or from the array.

Thus the phase distribution between the radiators of the array is used to control the main directional lobe of the over-all radiation pattern of the array. By controlling the phase distribution (for instance by the digital phase-shift-control means described in my said co-pending application), the angular position of the main lobe of the over-all radiation pattern can be varied, as for scanning purposes. This type of scanning is sometimes termed electronic scanning in contrast to the more conventional mechanical scanning which involves mechanically displacing an antenna.

Conventional electronic scanning, and more broadly the conventional control of the spatial configuration of the waves radiated by an array by acting on the phase distribution of the signals fed to and from the respective radiators of the array, has been found deficient in many respects. The radiating elements heretofore used in such arrays have generally been omnidirectional in character, arranged at a

spacing greater than half the operating wavelength. With such an array, the over-all radiation pattern has a central or main lobe and a pair of secondary lobes substantially symmetrically positioned on opposite sides of the main lobe. For large deviation angles of the main lobe of the array, e.g. for antenna scanning angles approaching $\pm 90^\circ$, one of the secondary lobes increases inordinately in field strength, so as to become comparable to the main or central lobe. The directional characteristics of the system are then seriously disturbed; for example, spurious target echoes are introduced into a radar system. To obviate this, the deflection angles, i.e. the scanning range, have had to be drastically limited.

If directional sources, rather than omnidirectional ones, are used as the elementary radiators of the array, then the width of the main lobe of each radiator again sets a definite limit to the maximum scanning angle achievable without excessively reducing the gain of the array.

Another defect of such conventional radiator arrays is that objectionable interaction or coupling occurs between adjacent radiators of the array, producing differential variations in the elementary radiation patterns of the radiators as the deflection angle (or scanning direction) is varied, with corresponding uncontrollable variations in antenna gain over the scanning range.

The present invention is based on the finding that the above and analogous deficiencies of conventional radiator arrays and electronic scanning systems using the same can be effectively eliminated if the field-distribution pattern, in respect to both amplitude and phase, of the energy fed to or from the individual radiators and the inter-radiator spacing are correlated, in accordance with certain definite teachings, with the spatial configuration of the waves that are to be radiated by the array.

This invention represents a development in the application of "signal theory" to antenna design and construction. The theoretical principles of the application of signal theory to radio antennas have been published previously by me in L'Onde Electrique, May 1965, page 550 et seq., in an article entitled "Application de la Théorie du Signal aux Antennes." The underlying idea can be summarized by saying that all statements and mathematical equations that are true for signal systems are also true for antenna systems, provided suitable changes are made in the variables involved so that, in essence, "time" is converted to "space." Thus, in particular, the field-distribution pattern of the energy fed to an antenna is regarded as an input signal fed to a signal transfer system, and the radiation pattern of the antenna is regarded as the output signal of the system. The antenna itself then assumes the role of a signal-transfer system, such as a filter, having a certain well-defined transfer function, which governs the conversion of the input signal into the output signal.

It will thus be seen that the great fund of knowledge built up over recent years in regard to signal-processing systems, becomes available for the study and development of antenna systems and, as already mentioned above, the present invention constitutes one particular, and important, result encountered along this line of investigation.

Referring to the linear array shown in FIG. 1, consider a continuous radiating source corresponding in over-all shape with that of the array, such as a narrow slot-like radiating aperture of the length d . The field distribution of such a continuous linear radiator can be shown to be representable by a complex function of the form

$$F(x) = A(x) \exp \{j\phi(x)\} \quad (1)$$

where $A(x)$, the modulus of the complex function, represents the amplitude distribution of the electric field along the O-X axis, and $\phi(x)$ represents the phase-angle distribution of the electric field along said axis.

Further, since it is known from classic signal theory that the frequency spectrum of a signal and the law of variation of said signal with time are Fourier transforms of each other, it can be shown that in analogous fashion

the radiation pattern of a continuous radiator can be represented as the Fourier transform $\psi(\alpha)$ of the field-distribution function $F(x)$, where α is the angular coordinate as indicated in the drawing. In the usual cases, the Fourier transform will be identically zero for angles α outside of a certain angular interval $(-\alpha_1, +\alpha_1)$; that is, the source does not radiate any field outside such interval. It will here be assumed that this condition is fulfilled. Under this condition, the field function can be subjected to a "sampling" operation, which is analogous to the "sampling" operation described by Shannon in respect to time-limited signals, and sometimes known as Shannon's theorem (cf. "Information Theory" by Stanford Goldman, ch. II, Prentice-Hall Inc., New York 1955).

Thus, by applying a sampling operation similar to that taught by Shannon with reference to time signals, the complex field-distribution function $F(x)$ given by Equation 1, above, can be broken down into a sum of terms

$$F(x) \sum_K \frac{\sin \pi \left(\frac{2x \sin \alpha_1}{\lambda} - K \right)}{\pi \left(\frac{2x \sin \alpha_1}{\lambda} - K \right)} F \left(\frac{K}{2 \sin \alpha_1} \right) \quad (2)$$

where k represents an integer, and λ the wavelength to be radiated. The factor

$$\frac{1}{2 \sin \alpha_1}$$

represents the "sampling interval" (which may be designated $\Delta\nu$ for convenience). It is of interest to note that the ratio (x/λ) , conveniently designated ν , represents a "space frequency."

According to the present invention, the array is so constructed that the individual radiators therein are spaced a uniform distance apart, substantially equal to the product of the "sampling interval" (as defined above), and the wavelength, i.e. the spacing a is given by

$$a = \frac{\lambda}{2 \sin \alpha_1}$$

Further, the field-strength distribution and phase distribution for the respective radiators of the array are taken in accordance with the terms of the sum 2.

By introducing the radiator spacing a as just defined, Equation 2 can be rewritten in homogeneous form

$$F(x/\lambda) = \sum_K \frac{\sin \pi \left(\frac{x}{a} - K \right)}{\pi \left(\frac{x}{a} - K \right)} F \left(\frac{K}{\lambda} \right) \quad (3)$$

With the array constructed as just specified, the overall radiation diagram of the array is substantially the same as the radiation diagram of the imaginary continuous radiation source, coextensive with the array, in respect to radiated waves having the prescribed configuration as described by the complex function

$$F \left(\frac{x}{\lambda} \right)$$

If the complex distribution function

$$F \left(\frac{x}{\lambda} \right)$$

represents an equiamplitude field-distribution pattern, which is a frequent case in practice, then the term $A(x)$ in Equation 1 is a constant and the field-distribution function takes the reduced form

$$F \left(\frac{x}{\lambda} \right) = \exp j\phi \left(\frac{x}{\lambda} \right) \quad (4)$$

and in Equation 3, the second factor of each term becomes

$$F \left(\frac{K}{\lambda} \right) = \exp j\phi \left(K \frac{a}{\lambda} \right) \quad (5)$$

5 The array will then be made up of a series of equispaced radiators at the spacing

$$a = \frac{\lambda}{2 \sin \alpha_1}$$

10 each radiator having a field-distribution pattern of the form

$$f_K(x) = \frac{\sin \pi \left(\frac{x}{a} - K \right)}{\pi \left(\frac{x}{a} - K \right)} \quad (6)$$

15 where K represents the position of the radiator in the array. Furthermore, the phase displacement between the signals fed to (or from) adjacent radiators of the array is given by the expression

$$\phi \left(K \frac{a}{\lambda} \right)$$

20 25 It will be noted that the radiation diagram of each radiator is a sectoral diagram limited to the angular range $(-\alpha_1, +\alpha_1)$.

The teachings of the invention will now be applied to two special cases. The first case relates to the construction of a radiator array usable for large-angle electronic scanning. The array may serve as an antenna array for transmitting planar waves in controllable directions within a prescribed scanning interval, and for receiving echo waves from the same directions.

25 30 Considering the imaginary continuous slot radiator of length d , it is apparent from elementary geometric considerations that in the case of a planar wave, radiated by the array in a direction at an angle α to the normal I-Z, the phase distribution of the energy along the slot aperture must vary linearly with the distance x as counted from the array extremity O, in accordance with the equation

$$\phi \left(\frac{x}{\lambda} \right) = \frac{2\pi x}{\lambda} \sin \alpha \quad (7)$$

35 40 45 Since the wave configuration is in this case equiamplitude, the complex field distribution

$$F \left(\frac{x}{\lambda} \right)$$

50 is of the reduced form given as Equation 4 above, i.e.

$$F \left(\frac{x}{\lambda} \right) = \exp \left\{ \frac{2\pi jx}{\lambda} \sin \alpha \right\} \quad (8)$$

55 Further the inter-radiator spacing is taken equal to

$$\frac{\lambda}{2 \sin \alpha_1}$$

as indicated above.

60 65 It is important to note that the radiation diagram of such a source, as given by the Fourier transform $\psi(\alpha)$, is sectionally continuous over the finite angular interval $(-\alpha_1, +\alpha_1)$, and consequently the sampling of the

$$F \left(\frac{x}{\lambda} \right)$$

70 75 function in accordance with the transposed Shannon's theorem is legitimate over that interval.

A radiating array according to the embodiment of the invention being described is partly shown in FIG. 2 as comprising a number of horn radiators 1, 2, 3, ... The radiators are spaced by the uniform distance $a = \lambda/2 \sin \alpha_1$. All the horns are supplied from a common signal source not shown, through conventional feeders which may include hybrid junctions. Interposed in the feeder connections 11, 21, 31, . . . of the respective horns are

phase shifters 19, 29, 39, . . . which impart respective phase shifts ϕ_1, ϕ_2, ϕ_3 to the signals applied to the radiators 1, 2, 3, respectively. The relative phase shift $(\phi_2 - \phi_1) = (\phi_3 - \phi_2) = \dots = \Delta\phi$ between adjacent radiators is readily determined from the phase-distribution Equation 7 of the array. If x_i and x_{i+1} are the abscissae of any two adjacent radiators in the array, then Equation 7 immediately gives

$$\Delta\phi = \phi(x_{i+1}) - \phi(x_i) = \frac{2\pi(x_{i+1} - x_i)}{\lambda} \sin \alpha$$

and since

$$(x_{i+1} - x_i) = a = \frac{\lambda}{2 \sin \alpha}$$

it is seen that

$$\Delta\phi = \pi \frac{\sin \alpha}{\sin \alpha_1}$$

The phase shifters such as 19, 29, etc. may assume any suitable form. If the desired deflection angle α is constant, then fixed phase shifters, such as suitably predetermined lengths of waveguide, may be used. If on the other hand the angle α is to be adjustable, such as in the scanning application considered above, then adjustable phase shifters are used, conveniently the digitally controlled phase-shift units disclosed in my co-pending application identified above.

In accordance with an essential feature of the invention, described above, the radiators 1, 2, 3, . . . must provide a field-strength-distribution pattern (or illumination law) at the fictive, continuous radiating aperture, represented by the line O-X, which is of the form given by Equation 6 above. The individual field patterns for the radiators 1, 2, 3, . . . are obtained by assigning the consecutive integral values 0, 1, 2, . . . to the term K in that equation, viz.:

Radiator 1;

$$f_0(x) = \frac{\sin \frac{\pi x}{a}}{\frac{x}{a}}$$

Radiator 2;

$$f_1(x) = \frac{\sin \left(\frac{\pi x}{a} - \pi \right)}{\frac{\pi x}{a} - \pi}$$

Radiator 3;

$$f_2(x) = \frac{\sin \left(\frac{2\pi x}{a} - 2\pi \right)}{\frac{2\pi x}{a} - 2\pi}$$

and so on.

It will be apparent that the field-distribution function for all the individual radiators is the same, being of the general form

$$\sin X/X$$

where X represents the abscissa as measured along the direction of the fictive radiating aperture, referred to an origin selected at one side edge of the radiator considered, and multiplied by the constant coefficient π/a , i.e.,

$$X = \frac{\pi}{a} (x - ka)$$

The individual field-distribution curves are so displaced by the constant amount a along the direction of the abscissae, that the distributions relating to adjacent radiators are orthogonally related, that is, the initial point of zero field strength (or node) for one radiator coincides with the initial point of maximum field strength (or peak) for the next radiator. Owing to this orthogonal relationship, there is, essentially, no mutual coupling

between consecutive radiators in the array. In FIG. 2, the field-distribution laws relating to the first three radiators 1, 2 and 3 have been partially and approximately represented above the radiators.

Radiators having the desired field-distribution characteristics as specified by the equations given above can be constructed in various ways, well understood by those skilled in the art. Thus, suitably disposed arrays of dipoles and reflectors may be used. However, in accordance with preferred embodiments of the present invention, especially in the s-h-f and the higher u-h-f frequency bands, the radiators of the array are constructed in the form of "multimode" horn radiators, as disclosed in my co-pending application.

FIG. 3 illustrates one such form of construction.

The array shown in that figure may be considered as consisting of a series of juxtaposed dual radiating sections 10, 20, 30, . . . n0, adjacent ones of which have common feeder junctions 11, 21, 31, . . . n1. The dual sections 10 and n0 at the respective ends of the array are further connected at their outer sides with impedance-matching loads provided by suitable shorted waveguides 40 and 50 respectively. Each of the dual radiating sections, such as section 20 for instance, includes a radiating aperture 12, 22, 32, . . . n2 each bounded by two parallel separating walls such as 13 and 23 which extend generally along the axial mid-planes of the feeder junctions a pre-determined distance inward from the plane of the radiating aperture, as shown. Further, each dual radiating section such as section 20 has a pair of oblique side walls extending from the sides of the feeder junctions 11, 21 and converging V-wise so as to define two symmetrical channels, such as 24 and 25, between said sidewalls and the aforementioned separating walls 13 and 23. The channels 24 and 25 both terminate outwardly at the radiating aperture 22, while being separated from each other over at least part of their length by a central separating wall or septum 26.

The operation of a radiator array of this type will be more fully understood by having reference to my earlier application Ser. No. 315,949, filed Oct. 14, 1963, now Pat. No. 3,308,469.

For the purposes of the present disclosure, it is sufficient to indicate that wave energy applied to the feeder junctions 11, 21, 31, . . . is guided by said feeders and then through the channels such as 24 and 25, in the manner indicated by the dotted arrows, the energy from each feeder being equally distributed by the corresponding separating wall such as 13 or 23 between adjacent dual radiator sections. In each dual radiator section such as 20, the partial energies applied from the two feeder junctions such as 11 and 21, associated with that section, combine at the radiating aperture such as 22 so as to provide thereat a resultant field which is the vector sum of the fields derived from the two associated feeder junctions. By this method of summation, it is possible to provide at the radiating aperture of each dual radiating section any desired pattern of field-amplitude distribution, with a high degree of approximation. For this reason the portion of each radiator section such as 20 comprising the two channels 24 and 25, outwardly bounded by the separating walls 13 and 23, is called a mode-selector or "moder" section of the radiator. The moders can operate in either the transverse electric or the transverse-magnetic modes, and in the illustrated embodiment transverse-electric operation is contemplated, with the E vector at the radiating aperture such as 22 extending perpendicular to the plane of the drawing. As explained more fully in the above-identified Pat. No. 3,308,469 a mode-selective radiator of the type just disclosed makes it readily possible to obtain at the radiating aperture thereof a field-distribution pattern which closely approaches the function

$$\frac{\sin X}{X}$$

at any rate as regards the main or central lobe and the first side lobes of the distribution curve. This is indicated in the upper part of FIG. 3, where the field amplitude distribution associated with each dual radiator section is represented above that section as a pair of symmetrical curves, one shown in full lines and the other dotted, which are respectively created by the energy applied to the respective feeders, such as 21 and 31, associated with the dual radiator section under consideration. As will be easily understood, the array of FIG. 3, instead of being regarded as being composed of a series of juxtaposed dual radiator sections as disclosed above, may just as well be considered as being made up of a series of juxtaposed horn radiators each being coaxial with a feeder junction such as 21 and having its radiating aperture divided by a separating wall such as 23. When the array is so considered, it will be seen that each elementary horn radiator therein has a field-amplitude-distribution pattern which is represented substantially as the central portion (main lobe and part of each of the first side lobes) of the curve

$$\frac{\sin X}{X}$$

these distribution curves overlapping as shown.

It will be understood that the energy fed to each of the feeder junctions 11, 21, 31 . . . of the array in FIG. 3 is applied by way of a related phase shifter 19, 29, 39, . . . as described with reference to FIG. 2, these phase shifters introducing progressive phase shifts such that the phases of the waves applied to adjacent feeder junctions differ by a desired constant angle, corresponding to the desired inclination angle for the plane wave radiated by the array, as earlier described.

As is known, the directional pattern of a linear array can be represented as a function of the form

$$A(\theta) = B(\theta)C(\theta)$$

where $A(\theta)$ represents the relative field strength of the array and is seen to be the product of two functions or factors. Function $B(\theta)$ characterizes any one of the elements of the array and represents the radiation diagram of such element, while function $C(\theta)$ characterizes the geometry of the array and represents the radiation diagram of an array in which the individual radiators are disposed in the same manner as in the array under consideration, but wherein said individual radiators are omnidirectional in character. For an array of the type here considered, function $C(\theta)$ represents a curve of the form shown in FIG. 4 for a scanning direction axially of the array, that is, for the case where the plane waves radiated by the array have zero inclination. When the scanning angle of said plane waves is varied by varying the phase-shift angle between the wave energy fed to adjacent feeder junctions of the array as above explained, the curve $C(\theta)$ in FIG. 4 is simply shifted by a corresponding amount along the axis of abscissae. It is manifest therefore that if the radiated plane waves are to retain a constant amplitude for all scanning directions within the scanning range $(-\alpha_1, \alpha_1)$ and to prevent the occurrence of substantial secondary lobes in the radiation pattern of the array within said scanning range, it is necessary that the function $B(\theta)$ representing the directional diagram of each elementary radiator should be constant, i.e. each of the radiators must have a sectoral radiation pattern over the range $(-\theta_1, \theta_1)$, as shown. Such a sectoral pattern, characterizing each of the elementary radiators in an array according to the invention, means that the elementary radiator must have an illumination law of the form

$$\frac{\sin X}{X}$$

as earlier stated. The discussion just given thus constitutes an alternative proof of the inventive condition regarding the form of the field-amplitude-distribution law for the in-

dividual radiators in the arrays of the invention, for optimal scanning performance.

A further embodiment of the invention will now be described with reference to FIG. 5, which schematically illustrates the invention as applied to spherical, rather than plane, radiated waves. The system shown in FIG. 5 comprises a primary radiator schematically indicated as the source S, e.g. a horn antenna, and a secondary radiating array comprising a series of radiators 1, 2, . . . , n, e.g. horn antennas, all positioned in mutually irradiating relation with the source S. Assuming electromagnetic energy is fed by conventional feeder means not shown to the primary antenna S, the latter will radiate spherical waves; it is desired that the secondary array shall receive the whole of the energy contained in the portion of the spherical wave limited to the angle $2\alpha_2$ defined by the width d of the array without any loss in gain. If conversely it is assumed that energy is fed to the secondary radiators 1, 2, . . . , n of the array and is radiated therefrom towards the primary radiator S, it is desired that this radiant energy shall converge spherically at the point S as a focus so as to be absorbed wholly by the primary radiator without any loss (except for inevitable diffraction ring effect).

Applying the teachings of the invention to this particular wave configuration, we shall first seek to determine the ideal law or pattern of phase distribution that should obtain along a fictive continuous radiator coextensive with the secondary array, in order that the desired complete transfer of energy between such continuous radiator and the spherical waves centered at S shall occur. Considering a point A of said continuous radiator, at a distance x from the origin O (taken at one end of the array, as shown), the phase angle $\phi(x)$ at the point A clearly is $2\pi/\lambda$ times the propagation distance A-M, where M is the point of abscissa x on the spherical wave (shown in dashed lines), passing through O. From elementary geometric considerations it is readily found that

$$AM = \sqrt{R^2 + x(d-x)} - R$$

where R is the distance from the source S to the array and d the width of the array. Hence,

$$\phi(x) = \frac{2\pi}{\lambda} (\sqrt{R^2 + x(d-x)} - R) \quad (9)$$

Since in this case also an equiamplitude field distribution is clearly involved (the field amplitude is constant throughout the spherical surface of the wave), the complex field-distribution function can be written, from Equation 4, as:

$$F(x) = \exp \left\{ j \frac{2\pi}{\lambda} (\sqrt{R^2 + x(d-x)} - R) \right\}$$

The Fourier transform of this function $\psi(\alpha)$, which represents the directional diagram of the fictive continuous radiator coextensive with the array, is clearly sectionally continuous over the finite interval $(-\alpha_2, \alpha_2)$ since such directional diagram is substantially a sector of angle $2\alpha_2$. Hence, Shannon's transposed breakdown theorem is legitimately applicable to this case, and the "sampling interval" will have the value

$$\Delta\nu_2 = 1/(2 \sin \alpha_2) = \frac{1}{2} \sqrt{1 + \frac{4R^2}{d^2}}$$

Hence, in accordance with a second one of the three conditions of the invention, the spacing of the secondary radiators along the array will be

$$a = \lambda \Delta\nu_2 = \frac{\lambda}{2 \sin \alpha_2} = \frac{\lambda}{2} \sqrt{1 + \frac{4R^2}{d^2}}$$

According to the third of the three inventive conditions,

the field-amplitude distribution of the energy fed to each radiator is in accordance with the function

$$f_k(x) = \frac{\sin \pi \left(\frac{x}{a} - k \right)}{\pi \left(\frac{x}{a} - k \right)}$$

where k represents the serial number of the radiator in the array, and a has the value just specified.

Each of the radiators 1, 2, ..., n of the array of FIG. 5 may be constructed as a multi-mode source, in a general manner similar to that shown in FIG. 3. The radiators are fed by way of feeder junctions in which are interposed suitable phase shifters, adjusted to impart to the feed energy a phase shift of the value dictated by Equation 9. Thus, the phase shift applied to the k th radiator of the array is seen from that equation to be

$$\phi_k(x) = \phi(ka) = \frac{2\pi}{\lambda} (\sqrt{R^2 + ka(d-ka)} - R)$$

It will be noted that in the system of FIG. 5 the individual radiators of the secondary array receive the spherical waves radiated by the primary source S under varying incidence angles, decreasing from the center to the periphery of the array. The condition of the invention regarding the field-strength distribution of the feed energy to the individual radiators in accordance with a law of the form $(\sin X)/X$, resulting in a substantially sectoral radiation pattern for each of said radiators as earlier indicated, in this particular case ensures that the peripheral radiators will receive the energy radiated by the primary source without any reduction in gain as compared to the central radiators of the array. Thus the said condition contributes to assure optimal energy transfer to and from the array, in respect to the particular, here spherical, wave configuration considered.

For clarity of representation, all the arrays of the invention herein disclosed have been shown as linear or unidimensional arrays, and the disclosure has for simplicity referred primarily to arrays of this kind. It is immediately evident, however, that the teachings of the invention are directly applicable to two-dimensional, or surface, antenna arrays, and in fact the most useful practical embodiments of the invention would comprise arrays of this last-mentioned type. It is to be understood that in cases where the invention is applied to a two-dimensional array, i.e. an array with a plurality of parallel rows of radiators, each of the three basic teachings of the invention, respectively relating to radiator spacing, field-strength-distribution pattern for each radiator, and phase-distribution pattern along the array, should be applied separately to each of two coordinate directions of the array, which directions are conveniently taken as mutually orthogonal. The construction of the two-dimensional array will then be completely determined.

It will thus be seen that I have provided a wave-transmitting or wave-receiving system with at least one row of equispaced radiators which are so connected to their associated feeding means (e.g. waveguides) that the individual field-strength-distribution pattern of each radiator has the form

$$A(K) \cdot \exp j\phi(K) \frac{\sin X}{X}$$

wherein $A(K)$ and $\phi(K)$ are, respectively, an amplitude factor and a phase factor. Each of these factors is a function, identical for all radiators as shown above, of the integer K which counts the number of radiators from an end of the row; in the case of a planar wavefront parallel to the array, as discussed in connection with FIGS. 1 and 3, both these functions may be constants. The function X , having the value

$$\pi \left(\frac{x}{a} - K \right)$$

as given above, goes to 0 for $x = aK$ and becomes equal to π for $x = a(K+1)$. Thus, if we regard the units 1, 2 and 3 of FIG. 2 as, respectively, radiator No. 0 ($K=0$), radiator No. 1 ($K=1$) and radiator No. 2 ($K=2$), we find that X varies linearly from a point P_1 on one side of any radiator to a point P_2 on the opposite side thereof, each of these points being spaced by a distance $a/2$ from the radiator axis z , as specifically shown for radiator 2. The function

$$f(X) = \frac{\sin X}{X}$$

varies at the same time from a peak $f=1$ at point P_1 to a node $f=0$ at point P_2 along a curve which assumes the value $2/\pi$ at its intersection with axis z , i.e. midway along the range P_1-P_2 . The cophasal energization of two confronting sections of adjoining radiators from a common waveguide, e.g. as illustrated in FIG. 3 for sections 25 and 26 of radiators 22 and 32 connected to feeder 21 with phase shifter 29, generates an approximation of the above function as indicated by the graph of that figure.

What is claimed is:

1. A system for radiating electromagnetic waves of a prescribed geometric configuration, comprising:
an array of radiators having radiant apertures equi-spaced in at least one row;
and wave-feeding means connected to said radiators for imparting to each radiator a coherent radiation pattern substantially of the form

$$A(K) \cdot \exp j\phi(K) \frac{\sin X}{X}$$

where A is an amplitude factor, ϕ is a phase factor and X is a function of distance varying linearly along said row from 0 at a first point on one side of the radiator to π at a second point on the opposite side of that radiator, each of said points lying at a distance of substantially $a/2$ from the radiator axis where a is the spacing between successive radiators, K being an integer counting the number of radiators from one end of said row, the functions $A(K)$ and $\phi(K)$ being the same for all radiators.

2. A system as defined in claim 1 wherein at least one of said factors is a constant.

3. A system as defined in claim 1 wherein said wave-feeding means includes individual phase shifters for said radiators.

4. A system as defined in claim 3 wherein said phase shifters are set to impart to successive radiators progressively varying values of ϕ separated by substantially the same difference $\Delta\phi$ for any two consecutive radiators.

5. A system as defined in claim 3 wherein said phase shifters are set to impart to successive radiators different phase shifts establishing a substantially spherically curved overall pattern of radiation centered on a point remote from said row of apertures.

6. A system as defined in claim 3 wherein said phase shifters are adjustable.

7. A system as defined in claim 1 wherein said radiators are each divided into two sections lying on opposite sides of said axis, said wave-feeding means being cophasally connected to confronting sections of any two adjoining radiators.

8. A system for radiating electromagnetic waves of a prescribed geometric configuration, comprising:

an array of radiators having radiant apertures equi-spaced in at least one row, each of said radiators being divided into two symmetrical sections lying on opposite sides of an axis bisecting its aperture along said row; and
wave-feeding means connected to said radiators for imparting to each radiator a coherent radiation pattern varying along said row from a peak on one side of said axis to a node on the opposite side with an amplitude and a phase respectively deter-

mined by a factor $A(K)$ and a factor $\phi(K)$, said wave-feeding means including a plurality of feeders each cophasally connected to a pair of confronting sections of two adjoining radiators, K being an integer counting the number of radiators from one end of said row, the functions $A(K)$ and $\phi(K)$ being the same for all radiators.

9. A system as defined in claim 8 wherein said feeders are provided with individual phase shifters for varying the relative phasing of radiated wave energy from one radiator to the other.

10. A system as defined in claim 9 wherein said phase shifters are adjustable to provide substantially identical

but variable phase differences between successive pairs of radiators.
